UNITED STATES PATENT OFFICE.

DAVID S. KENNEDY, OF BROOKLYN, NEW YORK, ASSIGNOR TO MERGENTHALER LINO-TYPE COMPANY, A CORPORATION OF NEW YORK.

TYPOGRAPHICAL MACHINE.

1,396,125.

Specification of Letters Patent.

Patented Nov. 8, 1921.

Application filed November 8, 1919. Serial No. 336,582.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 This invention relates to typographical machines, such as linotype machines of the general organization represented in Letters Patent of the United States, No. 436,532 to O. Mergenthaler, wherein circulating matrices are released from a magazine in the order 15 in which their characters are to appear in print and then assembled in line, the composed line transferred to the face of a mold, the mold filled with molten metal to form a 20 slug or linotype against the matrices which produce the type characters thereon, and the matrices thereafter elevated and returned through distributing mechanism to the magazine from which they started. More particularly, it relates to machines equipped 25 with a plurality of magazines containing different matrix fonts, and any selected one of which may be brought into action at will.

In one class of such machines, the magazines are mounted in or carried by a so-called "shift-frame", which is arranged to be moved upwardly and downwardly in the machine frame to bring one or another of the magazines into coöperative relation to the assembling and distributing devices. In prior 30 constructions, the location of the selected magazines in proper registration with the coöperating devices has been troublesome, not only because of the inherent difficulty 35 of constructing the parts in the precise manner required, but also by reason of the wear and warping of the parts in use, and for other reasons.

The present invention aims to obviate the 40 foregoing objections and contemplates an arrangement which will positively insure the location of the operative magazine in proper registration with the assembling and distributing devices and this without requiring 45 such accurate workmanship in the manufacture of the various parts. The manner

in which this result is attained will be fully set forth in the detailed description to follow.

In the accompanying drawings, I have shown my improvements merely in preferred 55 form and by way of example, and obviously many changes and variations may be made therein and in their mode of application which will still be comprised within the spirit of my invention. Generally speaking, I desire it to be understood that I do not limit myself to any specific form or embodiment except in so far as such limitations are specified in the claims.

Referring to the drawings:

Figure 1 is a side elevation of a portion 60 of a linotype machine having my improvements embodied therein;

Fig. 2 is a similar view of the magazine structure, with the parts in one position;

Fig. 3 is a detail-view;

Fig. 4 is a view similar to Fig. 2, but showing the parts in a different position;

Fig. 5 is a top plan view of the parts shown in Fig. 4; and

Fig. 6 is a vertical section taken on the line 6-6 of Fig. 5.

The matrices X are stored according to font in the superposed channeled magazine A, four of which are shown herein but of 80 which a greater or less number might be employed if desired. The several magazines are mounted upon the separate base-frames A¹ conjointly constituting a "shift-frame", which is arranged to be moved upwardly 85 and downwardly in the fixed machine frame to bring any selected one of the magazines into operative relation to the channeled assembler entrance B and the channeled magazine-entrance C, the latter leading 90 from the distributor D. Each of the magazines A is provided with the matrix releasing escapements E, (Fig. 2), which, when the magazine is brought into operative position, are actuated through the medium of the pivoted levers E¹ and E² by the reeds E³ controlled in the usual way from the keyboard E⁴. The magazine shift-frame (Fig. 1) is carried by the sliding plunger L³ which is raised and lowered 100 within the sleeve O by screw-thread mechanism actuated through the connecting shaft

bell crank lever F^8 , push rod F^9 and circular swinging plate F^{10} , the latter being pivoted to the handle L^1 which is slidably arranged in the wheel L . The spring F^{11} 5 pulling rearwardly on one of the arms F^4 acts to hold the parts in their normal condition. As a result of this construction, in shifting the magazines, the handle L^1 is first pushed rearwardly against the action of 10 the spring F^{11} to draw the gage-bars F forwardly clear of the alining lugs F^2 and the wheel L is then rotated to raise or lower the magazines to bring the selected one into 15 operative position. In effecting this shifting operation, the selected magazine is brought to a level slightly above that it will eventually occupy (Fig. 2), whereupon the gage-bars F are immediately restored to active position by the spring F^{11} . The 20 handle L^1 is now operated to lower the magazines, which action brings the alining lugs F^2 on the base-frame of the selected magazine into engagement with the gage pieces F (Fig. 4), thereby locating said magazine in 25 proper transverse registration with the co-operating parts as before mentioned.

When one of the upper magazines is brought into use, the alining lugs F^2 on the base frames of the underlying magazines 30 would engage the gage-bars and prevent their return to active position, unless otherwise provided for. Hence, the gage bars F are formed in their rear edges with notches f which allow them to clear the alining lugs 35 at such time, these notches being made considerably wider than the alining lugs so as not to interfere with the lowering of the magazines which takes place in banking the operative magazine on the gage-bars. This 40 lowering of the magazines, however, is limited by the engagement of the alining lugs on the lowermost base frame with the bottom walls of the particular notches wherein they are located (Fig. 4). In the foregoing arrangement, the operator has merely to shift 45 the magazines in the required direction until the gage-bars are snapped into active position by their actuating spring for co-operation with the selected magazine, and 50 then to lower the magazines until their downward movement is arrested, which operation automatically brings about the location of the operative magazine in proper transverse registration with the assembling and 55 distributing devices.

The means herein employed to secure the lateral registration of the operative magazine are in the form of a pair of gage blocks or abutments G supported in the fixed 60 framework at opposite sides of the magazines in position to engage the outer faces of the alining lugs F^2 at the forward ends of the base frames A^1 . These blocks are slidably arranged on the lower walls of 65 laterally extending inclosing notches G^1

(Fig. 3) and are set and held in the required position therein by means of adjusting screws G^2 and clamping screws G^3 , the former bearing against the outer edges of the blocks, and the latter passing through 70 elongated slots formed therein. At their inner edges, the blocks are formed with alining surfaces G^4 and with oppositely beveled surfaces G^5 leading thereto. Accordingly, when a selected magazine is brought into 75 operative position, the alining lugs F^2 at the lower end of its base frame A^1 are automatically engaged with the gage-blocks G , whose beveled surfaces G^5 adjust said frame edgewise toward the left or right, as the 80 case may be, until the lining surfaces G^4 become engaged with the outer faces of the alining lugs, which engagement of the parts determines the lateral registration of the magazine with the assembler entrance B . 85 Hence, any faulty construction of the parts, or any disarrangement thereof from other causes, will be taken care of by the gage-blocks or abutments, which act automatically as the magazine is brought into operative position to locate it laterally in relation to the assembler entrance.

A similar set of gage-blocks G might be located at the upper end of the magazines to locate the selected one in proper lateral 95 registration with the magazine-entrance C . However, in the present instance, such lateral registration is insured by the plates O^2 attached to the inner faces of the brackets O^1 (Fig. 5) and which guide the magazine 100 shift frame in its vertical movements and prevent any lateral displacement thereof.

In the present embodiment, the location of the operative magazine in proper longitudinal position is effected by a pair of gage-blocks or abutments H supported in the fixed machine frame at opposite sides of the magazines in position to engage the forward faces of the alining lugs F^2 as the individual magazines are brought into use. These 110 gage blocks H (Fig. 6) are slidably arranged in fore and aft grooves or guideways H^1 wherein the blocks are confined by clamping screws H^3 passing through elongated slots formed therein. The proper position 115 of the gage-blocks is controlled and regulated by adjusting screws H^2 bearing against the forward edges thereof. At their rear edges the blocks H are formed with alining surfaces H^4 and beveled surfaces H^5 , so 120 that as a selected magazine is shifted into position, the lower alining lugs F^2 on its base frame are engaged with the beveled surfaces H^5 , which adjust the frame endwise if need be until the forward faces of its 125 alining lugs become engaged with the alining surfaces H^4 of the gage-blocks. In this way, the selected magazine is located independently in proper longitudinal position within the shift-frame for co-operation with 130

the assembler and magazine entrances, any irregularities or imperfections of the parts being entirely compensated for.

The removal of the individual magazines may be effected in any desired manner, such for instance as illustrated in the Rogers patent mentioned. However, in the present instance, an improved form of mechanism is employed for this purpose, such mechanism 10 being carried by the shift-frame and acting by its operation to separate the base-frames from each other by swinging them relatively about their respective pivots. The mechanism herein illustrated comprises a hand-lever J fixed to a transverse rock-shaft J^1 journaled in the collar portion L^4 of the sliding plunger L^3 and provided at its opposite ends with arms J^2 connected by links J^3 to the uppermost base-frame A^1 , the 15 links being pivoted to said base-frame by studs J^4 . Pivottally suspended from the studs J^4 are lost motion devices or lifting links J^5 , each formed with a pair of elongated slots J^6 wherein engage studs J^7 projecting laterally from the two intermediate base-frames, the lower slots being somewhat longer than the upper slots. In effecting the removal of the magazines, therefore, the 20 hand-lever J is drawn forwardly from the position shown in Fig. 1, which movement of the lever through the connections described swings the three upper base-frames upwardly about their respective pivots A^2 and spreads them apart, so that the desired 25 magazine may be drawn forwardly from its base-frame and replaced by another containing a different matrix font. It will be observed that, due to different extents of the slots J^6 , the above separation of the base frames takes place progressively; that is to say, the top base-frame is raised independently by the initial movement of the hand-lever J to an extent sufficient to separate it from the underlying base frame, which then 30 by the continued movement of the hand-lever is raised along with the top base-frame and separated from the next underlying base-frame, and the latter next lifted by the final movement of the hand-lever and separated 35 from the lowermost base-frame. It will be understood of course that, before operating the hand-lever J , the shift-frame should be raised sufficiently to locate the magazine to be removed at such level that 40 when the base-frames are separated, it will be raised above the assembler entrance B for withdrawal from the machine. It may also be noted that the connections between the hand-lever J and the respective base-frames are such as to permit said frames to be freely and independently adjusted in the manner before described.

As previously stated, I have shown my improvements only in preferred form and by way of example and as applied to a par-

ticular class of machine, but obviously many modifications and alterations therein and in their mode of application will suggest themselves to those skilled in the art without departure from the scope of the invention.

Having thus described my invention, its construction and mode of operation, what I claim and desire to secure by Letters Patent of the United States, is as follows:—

1. In a typographical machine, the combination of a channeled member, a plurality of channeled magazines shiftable to bring one or another into operative relation to said channeled member, means for effecting such shifting of the magazines, and means 75 arranged to coöperate with the selected magazine independently as it is brought into operative position and locate it in proper transverse registration with the coöperating channeled member.

2. In a typographical machine, the combination of a channeled member, a shift-frame equipped with a plurality of channeled magazines supported therein with a capacity for relative play in a facewise direction, means for moving the shift frame to bring one or another of the magazines into operative relation to said channeled member, and means for adjusting the selected magazine facewise within the shift frame as it is brought into operative position to locate it in proper transverse registration with the coöperating channeled member.

3. In a typographical machine, the combination of a channeled assembler-entrance, a channeled magazine-entrance leading from the distributor, an intermediate shift-frame equipped with a plurality of channeled magazines supported therein with a capacity for relative play in a facewise direction, means for moving the shift-frame to bring one or another of the magazines into operative relation to the two entrances, and means for adjusting the selected magazine bodily 100 facewise within the shift-frame as it is brought into operative position to locate it in proper transverse registration with the assembler-entrance and magazine-entrance, respectively.

4. In a typographical machine, the combination of a channeled member, a shift-frame equipped with a plurality of channeled magazines supported therein with a capacity for relative play in a facewise direction, 105 means for moving the shift-frame to bring one or another of the magazines into operative relation to said channeled member, and gage-devices upon which the selected magazine is caused to bank independently as it is brought into operative position and which adjust it facewise within the shift-frame to locate it in proper transverse registration with the coöperating channeled member.

5. In a typographical machine, the combi-

- nation of a channeled member, a plurality of channeled magazines, separate base-frames whereon the magazines are mounted, means for connecting the base-frames together with a capacity for relative play in a facewise direction, means for shifting the base-frames as a whole to bring one or another of the magazines into operative relation to said channeled member, and means for adjusting the base-frame of the selected magazine relatively to the other base-frames as said magazine is brought into operative position to locate it in proper transverse registration with the coöperating channeled member.
6. In a typographical machine, the combination of a channeled member, a plurality of channeled magazines, separate base-frames whereon the magazines are mounted and each provided at one end and at opposite sides with a pair of laterally projecting alining lugs, means for connecting the base-frames together with a capacity for relative play in a facewise direction, means for shifting the base-frames as a whole to bring one or another of the magazines into operative relation to said channeled member, and a pair of transverse gage-bars supported in the fixed machine frame at opposite sides of the magazines in position to engage the alining lugs on the base-frame of the selected magazine as the latter is brought into operative position and thus to adjust said magazine facewise and locate it in proper transverse registration with the coöperating channeled member.
7. In a typographical machine, the combination of a channeled assembler-entrance, a channeled magazine-entrance leading from the distributor, a plurality of intermediate channeled magazines, separate base-frames whereon the magazines are mounted and each formed at each end and at opposite sides with a pair of laterally projecting alining lugs, means for connecting the base-frames together with a capacity for relative play in a facewise direction, means for shifting the base-frames as a whole to bring one or another of the magazines into operative relation to the two entrances, and two pairs of transverse gage-bars supported in the fixed machine frame at opposite sides of the magazines in position to engage the alining lugs on the base-frame of the selected magazine as the latter is brought into operative position and thus to adjust said magazine facewise bodily and locate it in proper transverse registration with the assembler-entrance and magazine-entrance respectively.
8. In a typographical machine, the combination of a channeled member, a plurality of channeled magazines, separate base-frames whereon the magazines are mounted and each provided at one end and at opposite sides with a pair of laterally projecting alining lugs, means for connecting the base-frames together with a capacity for relative play in a facewise direction, means for shifting the base-frames as a whole to bring one or another of the magazines into operative relation to said channeled member, a pair of transverse gage-bars supported in the fixed machine frame at opposite sides of the magazines in position to engage the alining lugs on the base-frame of the selected magazine as the latter is brought into operative position and thus to adjust said magazine facewise and locate it in proper transverse registration with the coöperating channeled member, and means for moving the gage-bars to and from active position, for the purpose described.
9. A structure as specified in claim 8, characterized by the fact that the gage-bars therein recited are formed in one edge with notches which enable them to clear the alining lugs on other base-frames as they are moved to active position for engagement with those on the base-frame of the selected magazine.
10. A structure as specified in claim 8, characterized by the fact that the gage-bars therein recited are supported at their lower ends upon plain alining surfaces of the fixed machine frame and have their upper ends arranged in position to engage the under sides of the alining lugs on the base-frame of the selected magazine, whereby the adjustment of the latter is effected by banking the alining lugs of its base-frame upon said gage-bars.
11. A structure as specified in claim 8, and characterized by the fact that the means therein recited for moving the gage-bars to and from active position are controlled by the magazine shifting means, so as to insure the proper coördination of the parts.
12. In a typographical machine, the combination of a channeled member, a plurality of channeled magazines shiftable to bring one or another into operative relation to said channeled member, means for effecting such shifting of the magazines, and means arranged to coöperate with the selected magazine independently as it is brought into operative position to locate it edgewise in proper lateral registration with the coöperating channeled member.
13. In a typographical machine, the combination of a channeled member, a shift-frame equipped with a plurality of channeled magazines supported therein with a capacity for relative play in an edgewise direction, means for moving the shift-frame to bring one or another of the magazines into operative relation to said channeled member, and means for adjusting the selected magazine edgewise independently as it is brought into operative position to locate it in proper lateral registration with the coöperating channeled member.

cate it in proper lateral registration with the coöperating channeled member.

14. In a typographical machine, the combination of a channeled member, a plurality of channeled magazines, separate base-frames whereon the magazines are mounted, means for shifting the base-frames as a whole to bring one or another of the magazines into operative relation to said channeled member, and means for adjusting the base-frame of the selected magazine edge-wise relatively to the others as said magazine is brought into operative position to locate it in proper lateral registration with the coöperating channeled member.

15. In a typographical machine, the combination of a channeled member, a plurality of channeled magazines, separate base-frames whereon the magazines are mounted, means for shifting the base-frames as a whole to bring one or another of the magazines into operative relation to said channeled member, and a pair of gage-blocks or abutments supported in the fixed machine frame at opposite sides of the magazines in position to engage the base-frame of the selected magazine as the latter is brought into operative position and adjust said frame edgewise relatively to the others to locate the magazine thereon in proper lateral registration with the coöperating channeled member.

16. In a typographical machine, the combination of a plurality of magazines shiftable to bring one or another thereof into operative position, means for effecting such shifting of the magazines, and means arranged to coöperate with the selected magazine independently as it is brought into operative position and locate it in proper longitudinal position for coöperation with the other elements of the machine.

17. In a typographical machine, the combination of a shift-frame equipped with a plurality of magazines supported therein with a capacity for relative play in an endwise direction, means for moving the shift-frame to bring one or another of the magazines into operative position, and means for adjusting the selected magazine endwise independently as it is brought into operative position to locate it in proper longitudinal position within the shift frame for coöperation with the other elements of the machine.

18. In a typographical machine, the combination of a plurality of magazines, separate base-frames whereon the magazines are mounted, means for connecting the base-frames together with a capacity for relative play in an endwise direction, means for shifting the base-frames as a whole to bring one or another of the magazines into operative position, and means for adjusting the base-frame of the selected magazine endwise

relatively to the others as said magazine is brought into operative position to locate it in proper longitudinal position for coöperation with the other elements of the machine.

19. In a typographical machine, the combination of a plurality of magazines, separate base-frames whereon the magazines are mounted, means for connecting the base-frames together with a capacity for relative play in an endwise direction, means for shifting the base-frames as a whole to bring one or another of the magazines into operative position, a pair of gage-blocks or abutments supported in the fixed machine frame at opposite sides of the magazines in position to engage the base-frame of the selected magazine as the latter is brought into operative position and adjust said frame endwise relatively to the others to locate the magazine thereon in proper longitudinal position for coöperation with the other elements of the machine.

20. In a typographical machine, the combination of a channeled member, a plurality of channeled magazines shiftable to bring one or another into operative relation to said channeled member, means for effecting such shifting of the magazines, and devices arranged to coöperate with the selected magazine independently as it is brought into operative position and locate it both in proper transverse and lateral registration with the coöperating channeled member.

21. In a typographical machine, the combination of a channeled member, a shift-frame equipped with a plurality of channeled magazines supported therein with a capacity for relative play in facewise and edgewise directions, means for moving the shift-frame to bring one or another of the magazines into operative relation to said channeled member, and devices for adjusting the selected magazine both facewise and edgewise independently as it is brought into operative position to locate it in proper transverse and lateral registration with the coöperating channeled member.

22. In a typographical machine, the combination of a channeled member, a plurality of channeled magazines, separate base-frames whereon the magazines are mounted and each provided at one end and at opposite sides with a pair of laterally projecting alining lugs, means for connecting the base-frames together with a capacity for relative play in facewise and edgewise directions, means for shifting the base-frames as a whole to bring one or another of the magazines into operative relation to said channeled member, and two sets of gage-devices supported in the fixed machine frame at opposite sides of the magazines in position to engage the alining lugs on the base-frame of the selected magazine as the latter is

5 brought into operative position and acting by said engagement to locate said magazine both in proper transverse and lateral registration with the coöperating channeled member.

23. In a typographical machine, the combination of a channeled member, a plurality of magazines shiftable to bring one or another into operative position, means for 10 effecting such shifting of the magazines, and devices arranged to coöperate with the selected magazine independently as it is brought into operative position to locate it in proper transverse, lateral and longitudinal 15 relation to the other elements of the machine.

24. In a typographical machine, the combination of a channeled member, a shift-frame equipped with a plurality of channeled magazines supported therein with a capacity for relative play in facewise, edgewise and endwise directions, means for moving the shift-frame to bring one or another of the magazines into operative relation to 20 said channeled member, and devices for adjusting the selected magazine facewise, edgewise and endwise independently as it is brought into operative position to locate it in proper transverse, lateral and longitudinal 25 relation to the other elements of the machine.

25. In a typographical machine, the combination of a plurality of channeled magazines, separate base-frames whereon the 30 magazines are mounted and each provided at one end and at opposite sides with a pair of laterally projecting alining lugs, means for connecting the base-frames together with a capacity for relative play in facewise, 35 edgewise and endwise directions, means for shifting the base-frames as a whole to bring one or another of the magazines into operative position, and three sets of gage-devices supported in the fixed machine frame at 40 opposite sides of the magazines in position to engage the alining lugs on the base-frame of the selected magazine as it is brought into operative position, and acting by such engagement to adjust said frame facewise, 45 edgewise and endwise relatively to the other base-frames to locate the magazine thereon in proper transverse, lateral and longitudinal 50 relation to the other elements of the machine.

55 26. In a typographical machine, the combination of a plurality of magazines, separate base-frames whereon they are removably mounted, and mechanism for separating the base-frames from each other to permit 60 the removal of the magazines, said mechanism comprising a hand-lever, and connections therefrom to the base-frames arranged to effect the separating movements of said base-frames at successive stages in the operation of the hand lever.

27. In a typographical machine, the combination of a plurality of magazines, separate base-frames whereon they are removably mounted, and mechanism for separating the base-frames from each other to permit the removal of the magazines, said mechanism comprising a hand-lever connected to one base-frame, and lost motion devices connecting said base-frame to another base-frame, whereby the operation of the hand-lever will effect the movements of the base-frames progressively to bring about their separation. 70

28. In a typographical machine, the combination of a plurality of magazines, a shift-frame therefor comprising separate base-frames whereon the magazines are removably mounted, means for moving the shift-frame to bring one or another of the magazines into operative position, and mechanism for separating the base-frames from each other to permit the removal of the magazines, said mechanism comprising a hand-lever journaled in the shift-frame, and connections from said lever to the base-frames 80 arranged to effect the separating movements of said base-frames at successive stages in the operation of the hand lever. 85

29. In a typographical machine, the combination of a plurality of magazines, a shift-frame therefor comprising separate base-frames whereon the magazines are removably mounted, means for moving the shift-frame to bring one or another of the magazines into operative position, and mechanism 90 for separating the base-frames from each other to permit the removal of the magazines, said mechanism comprising a hand-lever journaled in the shift-frame and connected to one base-frame, and lost motion 95 devices connecting said base-frame to another base-frame, whereby the operation of the hand-lever will effect the movements of the base-frames progressively to bring about their separation. 100

30. In a typographical machine, the combination of a plurality of superposed magazines, a shift-frame therefor comprising separate base-frames whereon the magazines are removably mounted, means for moving 110 the shift-frame vertically to bring one or another of the magazines into operative position, and mechanism for separating the base-frames from each other to permit the removal of the magazines, said mechanism 115 comprising the hand-lever J , the rock shaft J^1 journaled in the shift-frame and connected by the arm J^2 and link J^3 to the uppermost base-frame, and the lifting link J^6 depending from the uppermost base-frame and formed with an elongated slot 120 wherein engages a stud J^7 projecting laterally from an underlying base-frame. 125

31. In a typographical machine, the combination of three or more magazines, sepa- 130

rate base-frames whereon the magazines are removably mounted, and mechanism acting by a single operation to separate the base-frames from each other at successive stages in the operation.

32. In a typographical machine, the combination of three or more magazines, a shift-frame therefor comprising separate base-frames whereon the magazines are removably mounted, means for moving the shift-frame to bring one or another of the magazines into operative position, and mechanism carried wholly by the shift-frame and acting by a single operation to separate the base-frames from each other.

33. In a typographical machine, the combination of a plurality of channeled magazines, means for shifting the magazines to bring one or another into operative position, a channeled member to coöperate with the

selected magazine, and means whereby such selected magazine is self-positioned with reference to said channeled member when brought into operative position.

34. In a typographical machine, the combination of a shift frame, equipped with a plurality of channeled magazines supported therein with a capacity for relative play, means for moving the shift frame to bring one or another of the magazines into operative position, a channeled member to coöperate with the selected magazine, and means whereby such selected magazine is self-positioned with reference to said channeled member when brought into operative position.

In testimony whereof, I have affixed my signature hereto.

DAVID S. KENNEDY.
